JOSEPH HADFIELD, OF NEW YORK, N. Y.

Letters Patent No. 73,714, dated January 28, 1868.

IMPROVED MACHINE FOR CUTTING SOAP.

The Schedule referred to in these Letters Patent and making part of the same.

TO ALL WHOM IT MAY CONCERN:

Be it known that I, JOSEPH HADFIELD, of 13 Rutgers Place, of New York city, county and State of New York, have invented a new and useful Improvement in Machinery for Cutting Soap; and I do hereby declare that the following is a clear, full, and exact description thereof, which will enable those skilled in the art to make and use the same, reference being had to the accompanying drawing, forming part of this specification, in which drawing—

Figure 1 represents a plan view of a machine that contains my improvement.

Figure 2 is a cross-section.

Figure 3 is a detached view, partly in section, of the cutter-frame.

This invention relates to machinery or apparatus for cutting slabs of soap into bars.

The letter A designates the frame which supports the operative parts, the said frame being provided with two sets of bars, 1 1, and one set of bars, 2 2, which extend from the front of the frame backwards as far as the cutting-frame R, on which bars, 1 2, the table of the machine is supported. The letter B designates a shaft placed transversely of the frame A, beneath the bars 1 2, and carrying pinions I' I', one of which is seen in fig. 2, which engage the teeth of racks E E, that are supported by and guided between the bars 1 1, above mentioned.

The said racks are, by means of said shaft and pinions, moved to and fro in their guides, and their motions are communicated to the follower D, and to the table C, which is beneath the follower, by the following means: The said racks are directly connected to the said follower by arms which extend upwards through slits, L L, made in the table, from near its front edge to near its rear edge, as is indicated by the numerals 3 3, fig. 1, so that the follower always moves along with the racks.

The table is moved towards the cutter-frame V by means of a spring-latch, K, which is secured beneath the surface of the front part of the table, in such a manner as to engage the under side of the follower when the latter is moving towards the right, observing fig. 2.

The said latch is placed at the centre of the width of the table, over the vacant space between the two central bars, 2 2, and it is opened so as to disconnect the table and follower by means of a cam, J, placed between said bars 2 2, in such a location that the cam operates on the tail of the latch, to throw it up at the time the rear end of the table has reached the cutter-frame.

The object of the movable table C is to support and present the slab of soap to the revolving printing-roller M, by which it is marked or printed with the name of the manufacturer, or other characters.

The said printing-roller, M, is mounted in boxes, which are arranged to have vertical motion in the frames N by means of the screws O O; and said roller is constructed of rings or collars, placed next to each other on a plain cylinder, such rings or collars having on their periphery whatever letters or characters are to be impressed on the soap. The roller M is rotated from shaft B by means of a train of gearing, I F F' F'', seen in fig. 1, and partly seen in fig. 2, the gear-wheel I being on one end of the shaft B, and the gear-wheel F on the corresponding end of the printing-roller, while the intermediate wheels are on the hinged bars G H. The bar G extends downwards from the end of the printing-roller, its upper end being hung loosely on the journal of the wheel F, while its lower end is placed loosely on the stud which carries the intermediate gear-wheel F''. The bar H is connected to the end of shaft B, so that it can turn thereon, and at its end it has a stud, on which is placed the said wheel F'', which engages with the gear-wheel I of the shaft, and also with wheel F, which is placed on a stud on bar G, in such a position as to engage both wheels F'' and F. The gear-wheels I, F, F', F'', and F'', are of the same diameter, consequently the printing-roller and the racks E and table C are moved at the same speed and in the same direction, so that a slab of soap is moved beneath the printing-roller in such a manner that it is brought in contact with the roller, and becomes printed or impressed in parallel lines with the names or characters on the roller. When the table stops, through the operation of the cam J on its latch, the follower continues its movement, and pushes the slab of soap onwards towards and against the cutter-frame R, whose wires, z, divide the soap into strips, the edge of the follower being provided with slots, 4, which are arranged so as to be opposite the several wires, which consequently enter said slots after the soap has been cut entirely through, and the wires are thereby preserved from being injured or broken by contact with the follower.

The follower is fitted to move in guides in the upper part of frame A, and is so made and arranged as to be capable of removal from the machinery when it is desired to change or renew it.

I provide several followers for a machine, according to the changes in the cutter-frames, whose wires, z, may be arranged at greater or less distances apart, in order to produce bars of soap of different dimensions, the slots, 4, of the followers being arranged to correspond with the wires of the cutter-frame. The follower is attached to the machine by means of pins n n, which go through the arms that come up from the racks E, through the slots L in the table, the tops of said arms being received into recesses made in the under side of said follower, and being perforated to let the pins go through them, whereby the follower becomes securely locked to the said arms. When the follower is to be disconnected, the pins n n are drawn out, and the follower can then be lifted off the table.

In order to prevent the printing-roller from becoming clogged with soap, I keep its surface wet or moistened by means of a roller, Q, covered with flannel or other porous material, which roller is in contact with the printing-roller, so as to be turned by it, and is kept constantly saturated with water. The journals of said roller Q, one, or both, are placed in elastic bearings, so that the roller is kept constantly pressed against the printing-roller. The printing-roller is capable of adjustment by means of the adjusting-screws, O O, which raise or lower it in the frames N N, according to the thickness of the slabs of soap, and this adjustment is accomplished without disconnecting the gear-wheels F, F', F², and I, by means of the arrangement, above described, of the bars G H, which carry the intermediate wheels F' F².

The cutter-frame, seen detached in fig. 3, is so made that it can be removed at pleasure from the machine, in order to replace it with another whose wires, z, are at a different distance from each other.

The cutter-frame is connected to the frame, A, of the machine by placing its ends in vertical grooves formed in the blocks j j, one of which is made removable, to allow me to change the same at pleasure.

The cutter-frame is made in the following manner: To the bar S, I connect the upright end-pieces U U, upon which I place the top adjustable bar T, using guide-pins, W W, to keep the bar T always in the proper position on the uprights.

The bars S T are each perforated vertically with holes, at a suitable distance apart for the positions the cutting-wires are to occupy, and through said holes I insert a continuous strand of wire, beginning at either end of the cutter-frame, and going towards the other, from one hole to the next, in the manner shown in fig. 3, fastening the ends of the wire permanently at the ends of the cutter-frame. The vertical portions of the wire must be perfectly straight and parallel; and, in order to bring them to this condition, I exert a strain upon them by means of the screws X X and Y, and the truss V. The said truss is an arc-shaped piece of wood or metal, whose ends are let into recesses formed in the top of the bar T, near its ends, the ends of the truss being there held by means of the adjusting-screws, X X, which go through them and the bar T, their ends working against the upper surface of the upright U. The thread of the adjusting-screw Y works in the bar T, and its upper smooth part goes through the centre of truss V, to which it is held by means of collars, m m, so that it cannot advance or recede, whereby, when the said screw is rotated, it operates to force the bar T away from or draw it towards the truss, thereby straining or slackening the wire. The adjusting-screws X X operate to force the two bars S T apart, and thereby the wire is also strained.

When the slab of soap has been forced past the cutter-frame R, it is found divided into bars and lying on the stationary table g behind said frame, the slots 4 of the follower allowing the edge of the divisions in the edge of the said follower to go between the cutters z, and push the soap clear of the said cutters. The shaft B is next rotated in the opposite direction, whereby the racks and the follower are drawn forward to the position seen in fig. 1, the movable table C being also returned to its first position by means of the arms which connect the racks to the follower, and which arms strike the front ends of slots L I, and draw the table forward with the racks, in readiness to receive another slab of soap. This movement of shaft B is made use of to divide the several bars of soap on table g by means of the following devices: From the ends of shaft B, but within the sides of frame A, extend two belts, a, one of which is seen in fig. 2, which belts go through pulleys b, placed on the inner sides of the said frame A, and thence are taken upwards to rods c, which move within vertical tubes, d, whose inner sides are open, as seen in fig. 2. The upper ends of the rods c are connected to the springs e e, placed above, on the upper part of frame A.

The rods c are connected to each other by a transverse cutting-wire, f, which is moved upwards and downwards along with the rods c, which are themselves drawn downwards with the return movement of shaft B, by means of the bands a, which are then wound upon the shaft, the wire f, when it has divided the bars of soap transversely, being permitted to clear them by descending below the table g through the slot h therein. When the bands a are unwound from the shaft, the rods are lifted, and the slack of the bands is taken up by the springs e e, and the wire f is thereby brought again above the table, in readiness for cutting the next lot of soap transversely.

What I claim as new, and desire to secure by Letters Patent, is—

1. The combination and arrangement of the movable table C, the follower D, and the racks E E, which are attached, as specified, to the follower, substantially as described.
2. The arrangement and combination of the latch K, attached to the table C, with the cam J, for the purpose of detaching the table from the follower, substantially as described.
3. Making the follower D separate and detachable from the rest of the machine, and attaching it thereto by means of removable pins n n, substantially as described, for the purpose of being able to change the follower at pleasure.
4. The arrangement and combination, with the printing-roller M, of the bars G H, and the gear-wheels F, F', F², and I, substantially as and for the purpose described.

5. The moistening-roller Q, arranged and combined with the printing-roller M, substantially as and for the purpose described.

6. The cutting-frame R, made substantially as described, with the truss V, and straining-screws X X Y, for tightening the wire z.

7. Making the several cutters of the cutting-frame of a single strand of wire, substantially as described.

8. The transverse cutting-wire f, combined and arranged substantially as described, with the sliding rods e, the slotted tubes d, the springs e, and the shaft B, whereby the soap is divided transversely during the return movement of the table.

This specification signed by me, this 25th day of November, 1867.

JOSEPH HADFIELD.
